UNITED STATES PATENT OFFICE.

OTHELLO SUTPHEN, OF ALBANY, NEW YORK.

FIRE-ESCAPE.

SPECIFICATION forming part of Letters Patent No. 268,959, dated December 12, 1882.

Application filed April 22, 1882. (No model.)

To all whom it may concern:

Be it known that I, OTHELLO SUTPHEN, of Albany, in the county of Albany and State of New York, have invented a new and Improved 5 Fire-Escape, of which the following is a full, clear, and exact description.

My invention relates to improvements in fire-escapes; and it consists in the peculiar construction and arrangement of parts, as herein- 10 after more fully set forth.

Reference is to be had to the accompanying drawings, forming part of this specification, in which similar letters of reference indicate corresponding parts in all the figures.

15 Figure 1 is a front elevation of my improved fire-escape applied to a building, and Fig. 2 is a side elevation of the fire-escape and section of the wall of a building.

A represents the wall of a building, near the 20 top of which is an opening, B, of suitable size and form for the purposes of my improved fire-escape; or it may be an ordinary window or a passage of any approved form or arrangement over the top of the wall and onto the roof, 25 where a reel, C, is located by journals D in bearings E, attached to the wall, as here shown, or to the roof, in any manner to support said reel, so that the chains F of a fire-escape ladder may be wound on and off said 30 reel in and out of the window or other opening or over the top of the wall, to be rolled up on the reel out of the way when not wanted for use, and to be pulled or otherwise let down quickly to the ground when wanted for use.

35 The reel will have a hand-wheel, R, or a crank for turning it. The ladder consists of the aforesaid chains F and metal step-rods G, connected together as shown, or in any approved way, to form a fire-proof ladder.

40 The plan here shown for connecting the steps and the chains consists of inserting the ends of the rods through the links of the chains and securing them by a check-nut, H, each side of the links; but they may be otherwise connected and secured.

45 I represents the struts at the ground or a little above to project the ladder outward for inclining it, so as to make it easier to climb; also, for drawing it taut, for steadiness, and 50 also to swing it clear of fire issuing from the

windows. The said struts are pivoted to the wall at J, and braces K are arranged in connection with them for applying tension to the ladder, the braces being pivoted to the wall at L and bearing at their lower ends on the 55 notched sections M of the struts, so that the chains are tightened by bearing the outer ends of the struts down and secured by the braces falling backward in the notches.

The ladder is made readily attachable to the 60 struts by the projecting ends N of the lower step, G, and the notches made for said projections in the under sides of the struts; but any other approved method of which the connection can be readily made may be used. 65

P represents the wire employed to draw the ladder off from the reel and out of the window, or over the top of the wall when the reel is located on the roof, and the dotted lines on reel, Fig. 2, show the position of the ladder when 70 the ladder is stored upon the reel preparatory for use when required.

It will be seen that with a ladder of this kind the top of the highest buildings may be scaled readily by the firemen, and it also forms 75 the means of escape as well.

To enable persons to reach the ladder from lower windows, the tension may be slackened temporarily by the braces K and struts I, so that the upper part of the ladder will fall 80 against the wall, and the ladder may be tightened again after the persons are mounted upon it for steadyng it, and also for swinging it beyond the fire issuing from lower windows.

Having thus fully described my invention, 85 what I claim as new, and desire to secure by Letters Patent, is—

1. The combination, with a fire-escape ladder, F G, suspended from the upper part of the wall of a building, of struts I, pivoted to 90 the wall at their inner ends and engaging with the ladder at their opposite ends, substantially as described.

2. The combination, with a fire-escape ladder, F G, suspended from the upper part of the wall of a building, of the struts I, pivoted to the wall at their inner ends and engaging with the ladder at their outer ends, and braces K, substantially as described. 95

3. The combination of struts I, pivoted to 100

the wall A, and provided with notches M and braces K, also pivoted to the wall, with a chain-ladder, F G, suspended from the upper part of the wall of a building, substantially as described.

4. The chain-ladder F G, suspended as described, struts I, and braces K, pivoted to the wall, as described, said ladder and struts be-

ing detachably connected by the extensions N of the ladder and the notches in the struts, substantially as set forth.

OTHELLO SUTPHEN.
